United States Patent Office

Des. 195,558
Patented July 2, 1963

195,558

MULTIMETER

Ira W. Simons, Columbus, Ohio, assignor to American
Brake Shoe Company, New York, N.Y., a corporation
of Delaware

Filed June 7, 1962, Ser. No. 70,465

Term of patent 14 years

(Cl. D26—1)

2.500

1.500

FIG. 4

FIG. 5

Fig. 5

FIGURE 1 is a front elevational view of a multimeter embodying the present design.

FIGURE 2 is a side elevational view thereof, it being understood that both sides are identical.

FIGURE 3 is a top plan view thereof.

FIGURE 4 is a rear view thereof.

FIGURE 5 is a perspective view of the present multimeter.

I claim:

The ornamental design for a multimeter, substantially as shown and described.
